UNITED STATES PATENT OFFICE.

HENRY STEPHENS, OF CLEVELAND, OHIO, ASSIGNOR TO THE INTERSTATE RAILWAY SUPPLY COMPANY, OF CLEVELAND, OHIO, A CORPORATION OF OHIO.

GUARD RAIL.

Application filed January 30, 1923. Serial No. 615,855.

To all whom it may concern:

Be it known that I, HENRY STEPHENS, a citizen of the United States, and a resident of Cleveland, county of Cuyahoga, and State of Ohio, have invented a new and useful Improvement in Guard Rails, of which the following is a specification, the principle of the invention being herein explained and the best mode in which I have contemplated applying that principle, so as to distinguish it from other inventions.

The present invention relates to guard rails for railroad construction and more particularly to a guard rail of the type which furnishes a supporting base for the bottom of the main rail, the base being formed integrally with the guard rail. More particularly the present guard rail embodies certain features of construction whereby the overall length of the rail is kept at a minimum and yet a construction which allows either end to be used in front of the frog point. The construction is such as to give great strength and durability with the least amount of metal possible. To the accomplishment of the foregoing and related ends, said invention, then consists of the means hereinafter fully described and particularly pointed out in the claims.

The accompanying drawing and the following description set forth in detail certain mechanism embodying the invention, such disclosed means constituting, however, but one of various mechanical forms in which the principle of the invention may be used.

In said accompanying drawing: —

Fig. 1 is a plan view of my improved guard rail; Fig. 2 is a side elevation of the same; Figs. 3, 4 and 5 are sectional views on the lines 3—3, 4—4, and 5—5 respectively of Fig. 1 and Fig. 6 is a plan view of a track crossover and frog point showing the position of the guard rail relative to the frog point.

In the present construction, one rail of a track is illustrated, the rail 1 being mounted above the usual wooden ties 2, the guard rail 3 as a unit being formed with transversely extending base plates 4 which rest upon the ties and extend under the rail 1, the base plates having spike receiving apertures 5 for securing the two rails in position.

The main rail 1 is of the usual construction having a head 6, a vertical web 7 and

base 8. The guard rail 3 is preferably an integral casting and comprises an upper or head portion 9 having a vertical web 10, the head and web having a central straight section and two outwardly curved end portions. At spaced points along the guard rail the vertical web 10 is extended downwardly into the base plates 4 which extend underneath the main rail, thus forming supporting piers.

To add strength to the guard rail, the parts above the base plates are reinforced by flanges or webs, there being two triangular shaped reinforcing flanges 11 which extend from the guard rail head 9 to the outer edge of each base plate 4 and two smaller rectangular shaped flanges 12 extending from underneath the rail head 9 to each base plate 4 on the inner side of the rail. These latter two flanges 12 are spaced within the other two flanges 11. The guard rail between each two base plates is supplied with a reinforcing flange 13 on the inside and the lower edge of the vertical web is formed into a horizontal flange 14 which extends from one flange 11 to the adjacent flange 11 on the next base plate and these flanges 14 are curved outwardly at their ends to form arcuate horizontal reinforcing portions 15 adjacent the flanges 11 as best shown in Fig. 1. These parts are, of course, formed together as a single casting but due to the reinforcing flanges the structure is very rigid and strong. The sections between the base plates are strengthened by the horizontal flange 14 and the corner portions 15 as well as by the small vertical flanges 13 on the inside while the guard rail head is very strongly braced at the base plates by the two large triangular vertical webs as flanges 11 on the outside or away from the main rail, and by the two inwardly extending webs or flanges 12.

At the ends of the guard rail, removable foot guards 20 are used, these foot guards being castings each having a vertical, transverse end plate 21 and having a vertical longitudinal web 22 adapted to fit snugly against the vertical web 10 of the guard rail and being notched to receive the reinforcing flanges or webs 12. At the top the foot guard is provided with a trough 23 extending between the main rail and the guard rail as shown in Fig. 5 and the foot guards are bolted to the guard rail by bolts

100

110

24 passing through an aperture in the central part of the vertical web 22 where it fits between the flanges 12 and a suitable aperture formed in the vertical web of the guard rail.

The present guard rail presents great strength as the rail part proper is of Z bar shape and by means of the webs or flanges at the base plates the guard rail is strongly braced, the flanges or webs 11 being compression braces while the other webs 12 act as tension braces. The use of the horizontal flange of the rail Z bar with the horizontal corner braces 15 makes a horizontal arch construction of great strength with a minimum amount of metal. The base plates which with the braces form the supporting piers are extremely rigid and hold both the main rail and the guard rail securely. If desired, the inner face of the guard rail head 9 may be hardened to reduce wear and this is desirable in guard rails for certain uses.

In using guard rails it has been found necessary to have the guard rail extend approximately four feet ahead of the frog point and the straight portion of the guard rail or the portion parallel to the main rail must extend ahead of the frog point at least a distance equal to the distance between ties. Consequently integrally formed or unit type guard rails which have base plates for supporting the main rail have been made long enough to extend over five ties, the ends of the guard rail resting on the end ties and having the center point opposite the frog point on the center tie as the frog point is always located on a tie. By so making a guard rail the straight portion extending ahead of the frog point is equal to the distance between ties and the further extending curved portion equal to the distance between ties. Thus the portion of the guard rail parallel to the main rail is approximately twice as long as either curved end as there is as much straight portion behind the frog point as in front thereof.

In the present guard rail the length is reduced and the rail spans only four ties but overhangs slightly at each end. The present guard rail may be considered as of three sections, two outer curved sections *a* and a central straight section *b*, each section being of approximately the same length.

In use as illustrated in Fig. 6, the present guard rail for either outside track 49 is placed with the rear end of the central section *b* opposite the frog point 50, that is with the frog point opposite the rear part of the straight portion and, as the two interior base plates rest on ties 51 and 52, with one interior base plate on the tie 51 opposite the frog point 50 and two piers or base plates ahead thereof. By thus arranging the straight and curved portions it has been

found possible to furnish a reversible guard rail of approximately six feet in length equally as satisfactory in use as former guard rails of about eight feet in length. Thus the total weight is reduced and the cost without 70 sacrificing strength or rail protection as it is only in front of the frog point that the rail is necessary.

Other modes of applying the principle of my invention may be employed instead 75 of the one explained, change being made as regards the mechanism herein disclosed, provided the means stated by any of the following claims or the equivalent of such stated means be employed.

I therefore particularly point out and distinctly claim as my invention:—

1. A guard rail for a switch frog adapted to be secured to four cross ties, having a short central tangent portion of a length 85 approximately equal to the distance from the frog point to the throat of the frog, and a wing portion of substantially equal length thereto at each end of said tangent portion, integral plates formed at 90 approximately the meeting line of the tangent with each wing portion and adjacent the outer ends of each wing portion, whereby said guard rail may have the greater portion of the tangent section and one wing 95 section disposed in advance of the frog point of a switch a distance of two ties, integral compression braces formed vertically on the outer faces of said guard rail in alignment with said plates and tension braces integrally formed on the inner face of said guard rail in vertical alignment with said plates. 100

2. A guard rail comprising a series of base plates and a rail of Z-bar shape formed integrally therewith having a continuous 105 vertical web and having its head section projecting toward the running rail, and braces between said rail bar and base plates comprising two compression webs on the outside of said Z-bar and two tension webs on 110 the inside of said Z-bar at each base plate.

3. A guard rail comprising an extending rail of Z-shape having a head section projecting toward the running rail and a continuous vertical web, a series of supporting 115 piers, formed integrally therewith, said piers comprising base plates adapted to extend under a main rail and outwardly beyond the guard rail, compression braces extending from the guard rail head to such 120 outwardly extending base plates, and tension braces extending from under said rail head to said base plates on the inside of said guard rail.

4. In guard rail construction, a unitary 125 structure comprising a guard rail of Z-shape having a rail head projecting toward the running rail, a continuous vertical web and an outwardly extending lower horizontal flange, a plurality of piers formed inte- 130

grally along said rail and adapted to form the supports for said rail, said piers comprising a base plate of inverted **T** section provided with compression webs on the outside and tension webs on the inside and formed with corner braces connecting with said lower horizontal flange of the rail section.

5. In guard rail construction, a unitary structure comprising a guard rail of **Z** shape having a rail head projecting toward the running rail, a continuous vertical web and an outwardly extending lower horizontal flange, a plurality of piers formed integrally along said rail and adapted to form the supports for said rail, said piers comprising a base plate of inverted **T** section provided with two compression webs on the outside extending from the rail head to the base plate and two tension webs on the inside extending from underneath said rail head to said base plate and spaced closer together than said compression webs, and formed with corner braces connecting with said lower horizontal flange of said rail.

10 15 20 formed with corner braces connecting with said lower horizontal flange of the rail.

6. In guard rail construction, a unitary structure comprising a guard rail of **Z** shape having a rail head projecting toward the running rail, a continuous vertical web and an outwardly extending lower horizontal flange, a plurality of piers formed integrally along said rail and adapted to form the supports for said rail, said piers comprising a base plate of inverted **T** section provided with two compression webs on the outside extending from the rail head to the base plate and two tension webs on the inside extending from underneath said rail head to said base plate and spaced closer together than said compression webs, and formed with corner braces connecting with said lower horizontal flange of said rail.

25 30 35 Signed by me this 24th day of January, 1923.

HENRY STEPHENS.
